FRANZ A. BOEDTCHER, OF BERGENFIELD, NEW JERSEY, ASSIGNOR TO OTIS ELEVATOR COMPANY, OF JERSEY CITY, NEW JERSEY, A CORPORATION OF NEW JERSEY

ELEVATOR-SIGNAL-RESTORATION SYSTEM

Application filed July 23, 1924. Serial No. 727,615.

This invention relates, generally speaking, to the signalling systems of elevators and more especially to that portion of such signalling systems as has to do with the cancellation, resetting or restoration of signals previously given. It is the common practice in systems of this general character to control the setting of one or more signals by the pressing of a passenger's push button at a floor, by the movements by an elevator car or through the conjoint action by both and to leave this signal or signals set until some predetermined act has been accomplished whereupon the signal or signals are reset. The present invention is directed to the restoration of a signal or signals after they are set in any suitable manner well known in the prior art and inasmuch as any suitable signalling means may be employed, I will confine my description solely to the resetting part of the signalling system and in this connection describe the structure, mode of operation and results obtained through the employment of the present invention.

One of the important objects of the invention from a practical standpoint is to provide a restoration system so organized that when a car, traveling in a predetermined direction, stops at a floor, intermediate the terminal floors of the building, and from which one or more signals have been sent, the car may stop at such floor, and upon leaving said floor in a retrograde direction, will automatically effect the cancellation or restoration of said signal or signals. This feature constitutes an important advance over the prior art and has not been heretofore accomplished by prior constructions which so function that unless the car proceeds from a floor in the same direction as it approached said floor, the signal or signals will not be cancelled.

Another object of the invention is to provide a restoration system so coordinated with the car that the car in starting away from or leaving a floor at which it has stopped will automatically bring about the restoration of the signals appropriate to the direction in which the car is taking.

without cancelling or restoring signals appropriate to the opposite direction. This restoration operation may in practice result from any suitable act of the operator which will bring about a starting of the car from the floor or from the actual movement of the car in leaving said floor, or from the incidental movements of the elevator controlling or operating mechanism either directly in the car or in the shaft or overhead, or two or more of these may combine to effect the result sought.

The signal to be reset through the employment of the present invention may be of any suitable character and may be positioned in any appropriate place. For example, the signals directly within the car and from which the operator receives notification of the desires of a prospective passenger, as well as the floor signals by which the passenger is apprised of the particular car which will render the service requested and other suitable signals are among those which the restoration system of this invention may be practically utilized for cancellation. It is of considerable practical importance that the floor signals in particular remain set until the car leaves the particular floor at which a passenger may be waiting service. It has been heretofore proposed to cancel or reset signals when the car comes to a stop at a floor and when such systems are in operation the floor lamps for example will immediately be deenergized when the car stops which is a pronounced disadvantage since the waiting passenger has no means of knowing at this time which car will render the service. With the present invention in contradistinction, the floor lamps at any given floor and appropriate to the particular direction in which the car will leave the floor will remain energized until the act of starting the car has taken place.

Objects and features of the invention, other than those specified, will be apparent from the hereinafter detailed description and claims, when read in conjunction with the accompanying drawings.

Speaking generally, the system of the

present invention embodies a suitable resetting magnet or its equivalent, the energization of which will effect the resetting or restoration of the signal or signals which have been set and which it is desired to cancel or restore. This magnet is appropriate to one direction and a separate magnet similarly constituted is provided for the opposite direction of movement of the car. In other words, there is an up restoring magnet and a down restoring magnet and with each of these magnets is associated a suitable circuit peculiar to that particular magnet although certain of these circuits may have common feeds or returns.

Each of these magnets is included in what may be termed a restoration circuit which is preferably a normally open circuit, but is adapted to be closed or completed by one or more switches. This switch or switches are operated to render the restoration circuit operative only when an associated car is in a predetermined zone and only when said car is in the act of leaving a floor from which the signal or signals have been sent and in a predetermined direction. In other words, the energization of the restoration circuit depends upon three factors, namely, the position of the car, the act of starting the car or movement of the car, and the direction in which the car leaves the floor.

In one of its preferred practical forms, although manifestly not the exclusive one, the resetting circuit may include beside the one resetting magnet and the restoration magnet, two switches, one of which is operated in synchronism with the car as the latter travels up and down the shaft and the other of which is operated by the starting or act of starting of the car after it has stopped at a floor. Of these switches, the first may conveniently partake of the form of a commutator, while the second may be in the form of a governor switch. The commutator will automatically select the floor and close the restoration circuit at this point, while the governor switch, controlled as it is by the starting or act of starting of the car, will control the closing of the circuit at the second point. Only when these two switches are properly coordinated can the restoration be accomplished and inasmuch as this coordination is accomplished automatically the appropriate signals will be automatically cancelled or reset without requiring thought or attention on the part of the car operator.

In the accompanying drawings, I have illustrated different wiring diagrams and mechanisms for carrying out the present invention, but the constructions therein shown are to be understood as illustrative, only, and not as defining the limits of the invention.

Figure 1 shows a wiring diagram of one

form of restoration system embodying the present invention and in this figure certain apparatus is shown in section on the line 1-1 of Figure 2.

Figure 2 shows a side elevation of the apparatus shown in Figure 1 with an additional wiring diagram associated therewith; and,

Figures 3 and 4 show other wiring diagrams embodying the present invention.

Referring first to the wiring diagram shown in Figure 1. I have shown a wiring diagram appropriate to two floors of a building and for a two car installation and it will be readily apparent to those skilled in the art how the wiring therein illustrated can be amplified for a greater number of floors and a greater number of cars.

We will assume for the purpose of concrete example that 3^a designates the up restoring device for the second floor, 3^d designates the down restoring magnet for the third floor and 2^a denotes the down restoring magnet for the second floor. These magnets or their equivalents serve to effect the restoration of the signal and they may act either directly upon the signal or upon a switch in the secondary circuit or in any other suitable manner well known in the art in order to effect the restoration.

4 designates the moving arm of the up commutator of one car which will be hereinafter termed car I. 5 designates the moving arm of the down commutator of car I, 6 the moving arm of the up commutator of car II, and 7 the moving arm of the down commutator of car II. All of these commutator arms 4, 5, 6 and 7 move in accordance with the movements of the car and in synchronism therewith as is common of commutators in this art and through their operation automatically select the floors at which the signals are to be cancelled. For example, the commutator arm 4 will be brought through the movement of the car into engagement with the contact 8 associated with the magnet 3^a and will, in turn, engage the contact 9 associated with the magnet 2^a. Similarly the arm 5 is adapted to be engaged with the contacts 10 and 11, while the arm 6 engages the contacts 12 and 13 and the arm 7 engages the contacts 14 and 15. Through the operations of these commutators, the particular floor is selected in an entirely automatic manner and corresponding to movements of the cars.

16 designates a suitable source of current supply which is connected by wires 17 and 18 to the magnets 2^a and 3^a and by the wires 17 and 19 to the magnets 3^d and 2^d. The contacts 8 and 12 are connected together by a wire 20, while the contacts 9 and 13 are connected by a wire 21. Similarly the contacts 10 and 14 are connected by a wire 22, while the contacts 11 and 15 are connected

5 by a wire 23. From the opposite pole of the source 16, a wire 24 leads through a branch 25 to a fixed contact 28' and through a branch 27 to a fixed contact 28. Associated with the fixed contacts 28' and 28 are spaced contacts 30' and 30. The contacts 28' and 30' are adapted to be bridged by a bridge piece 32', while the contacts 28 and 30 are adapted to be bridged by a 10 bridge piece 32. The structure of these bridge pieces and their mode of operation will be hereinafter more fully explained. From the contact 30' leads a wire 33, which has two branches 34 and 35.

15 The branch 34 leads to one contact of the up commutator switch 41' of car I while the branch 35 leads to one contact of the down commutator switch 42 of car I. Similarly the contact 30 is connected to a wire 36 having two branches 37 and 38. The branch 37 leads to one contact of the up commutator switch 41 of car II, while the branch 38 leads to one contact of the down commutator switch 42 of car II. An important 20 part of this invention resides in the fact that each of the branches 34, 35, 37 and 38 include governor control switches respectively designated generally by the reference characters 41', 42', 41 and 42. These governor switches may be of any suitable construction, but are controlled so as to be closed either by the actual starting of the car after stopping at a floor or by the act of bringing about the starting of the car such for example as the swinging of the controller lever out of neutral position and into a position to start the car in one direction or the other.

25 In any event, it will be apparent that if one of these governor switches is closed and the corresponding bridge piece is bridging the contacts 28' and 30' or 28 and 30, that current will flow from the source of electrical energy through the restoring magnet 5 which is included in the circuit by the particular commutator engaging with the corresponding contact. For example, if it be assumed that car II is leaving the second floor the commutator arm 7 will be in engagement with the contact 15, and the bridge piece 32 is bridging the contacts 28 and 30, so that if the governor switch 42 is closed even momentarily current will flow from the source of power through the down restoring magnet 2^a of the second floor and in so doing will effect the resetting of the signals appropriate to the second floor. The closing of the governor switch 42' of car I will similarly energize either 30 of the magnets 2^a or 3^a depending upon the position of the car, while the energization of magnets 2^a and 3^a is similarly accomplished, being controlled by the governor switches 41' and 41. As stated, the means for controlling the governor switches may vary

without departing from this invention, but for the purpose of illustration, I have shown a very practical and efficient form of apparatus in Figures 1 and 2.

35 Referring to these figures, 43 is a stub shaft mounted in fixed position upon a bracket 44 secured to any suitable rigid support. Rigid with the bracket is an insulating plate 45 shown as circular and coaxial with the shaft 43. Mounted for oscillation on the shaft 43 is a sleeve 46 to which a sprocket 47 is rigidly secured so that when the sprocket is rotated the sleeve 46 is simultaneously rotated. This sprocket is geared by a suitable sprocket chain to any 40 suitable part of the elevator operating mechanism so that as the elevator ascends the sleeve will be rotated in synchronism in one direction and as the elevator descends, this sleeve will be likewise rotated in synchronism in the opposite direction. By 45 these connections, therefore, the sleeve is made to rotate in a direction corresponding to the direction of movement of the car and for example it may be said that the sleeve rotates to the right when the car is descending and to the left when the car is ascending.

50 Cooperating with the sleeve is a clutch 48 formed of two pieces 49 and 50 hinged together at their tops as at 51 and formed with semi cylindrical cut-outs 52 adapted collectively to embrace the sleeve. The lower portions of the clutch elements are cut away and a magnet 53 is rigidly mounted on the clutch element 50 by riveting or threading its core 54 in place. The clutch element 49 is free and unattached with respect to the core of the magnet and constitutes the armature of said magnet. When the magnet 53 is deenergized, the cut away portions 52 will embrace the sleeve 46 so loosely as to permit free rotation of the sleeve within the clutch. However, when the magnet 53 is energized, the clutch sections 49 and 50 will be drawn tightly together so as to grip 55 the sleeve and receive tractive power therefrom, whereby the clutch will be bodily turned with the sleeve in a direction corresponding to the direction of rotation of said sleeve.

60 Mounted on the clutch is an insulating member 55 which carries a curved face shoe 56, and the governor switches 41 and 42 are so positioned that through the oscillation 65 of the clutch in the manner described this shoe will be moved to close either of said switches depending upon the direction of rotation of the sleeve. In practice, I preferably mount the governor switches on insulating blocks 57 and 58 which are carried by arms 59 and 60, respectively, and which arms are mounted for pivotal movement about the axis of the shaft 43, in such manner that the contacts 41^a and 41^b of the gov- 70

ernor switch 41, as well as the contacts 42^a and 42^b of the governor switch 42 will at all times lie in the path of travel of the shoe 56, and the pivotal mounting referred to will permit the circumferential adjustment of the governor switches for important practical reasons which will be hereinafter more fully explained.

The bridge piece 32 which has been hereinbefore referred to is mounted on and insulated from a locking latch 61. This latch is pivoted in a bracket 62 supported on the insulating plate 45. One end of the latch extends forwardly and overlies the upper end 15 of the clutch and is adapted to normally gravitate into engagement with a notch 63 formed in the insulating block 55 for the purpose of normally locking the clutch against rotation with the bridge piece free 20 from engagement with the contacts 28 and 30. The rear end of the latch projects over 25 and constitutes the armature of a magnet 64 which is also preferably mounted on the bracket 62 and it is through the energization of this magnet that the latch may be lifted to disengage the clutch and permit of its rotation to close either of the governor switches 41 or 42, while the bridge piece will simultaneously approach the contacts 28 and 30.

The magnet 64 is in practice either in 30 series or multiple with the magnet 53, and while the connections may vary, a very satisfactory form of connection is illustrated in the drawings. In this showing, one pole of the magnet 64 is connected by a wire 65 to a substantially semicircular segment 66 mounted on the forward face of the insulating plate 45. A wiper 67 carried by the clutch member 49 bears against this segment 40 and is connected by a wire 68 to one pole of the magnet 53. The other pole of the magnet 53 is connected by a wire 69 to a wiper 70 which bears against a second substantially semicircular segment 71 fixed on the plate 45. This latter segment is connected 45 by a wire 72 (see Figure 2) to a suitable source of electrical energy 73, while the return from said source is connected by the wires 74, 74^a to the magnet 64. It will be 50 noted, however, from Figure 2, that a switch mechanism is included between the wires 74 and 74^a and this switch mechanism will now be described.

75 is a car controller positioned in the car 55 and by means of which the movements of the car are controlled. This controller is of conventional form and serves the conventional purpose of starting or stopping the car and controlling the direction of movement of 60 said car. The controller is connected with the source of power 73 through suitable wiring which includes an up directional magnet 76^a and a down directional magnet 76^b. When the controller is moved in a direction 65 to cause the car to ascend the magnet 76^a is

energized and draws up one end of a pivoted rocker 77 to cause it to engage with a contact 78^a. When the controller is shifted to effect downward movement of the car, the magnet 76^b is energized and draws up the corresponding end of the rocker 77 to engage with the contact 79^a. The contacts 78^a and 79^a are connected with the operating motors of the car for up and down directions and the rocker is connected with a common return through the source of power to operate 70 said motors in the conventional manner.

It will be noted however that the opposite ends of the rocker 77 carry two movable contacts 80 and 81 which are adapted for cooperation with fixed contacts 82 and 83, respectively. The contacts 80 and 81 are both connected to the wire 74^a which leads to the magnet 64 while the contacts 82 and 83 are connected by a common return 84 to the source of power 73. With this arrangement, it will be apparent that when the controller is moved to effect either an up or down travel of the car, current will be caused to flow simultaneously through the two magnets 64 and 53 and in practice a spring, weight, or other suitable means is provided to shift the switching mechanism of which the rocker 77 and contacts 80 and 81 form a part in a neutral position when 95 the controller is in neutral position and the car at rest.

This arrangement which I have shown in Figure 2 is the preferred form of controlling the energizing of these magnets from the controller, although there are other ways in which this can be accomplished without departing from this invention and I accordingly do not limit the invention to the specific switch construction illustrated. 100 The mode of operation of the system as shown in Figures 1 and 2 in accomplishing the restoration of a signal or signals will 105 now be described in detail.

Let it be assumed that car II is at rest 110 at the third floor. The direction in which the car approaches the floor is immaterial to subsequent operations and this fact in itself clearly differentiates the present system from all prior practice. As car II 115 stands at the third floor from which presumably a signal has been sent, the signal or signals appropriate to this floor continue to function so long as the car is at rest. At this time the commutator arm 7 is in 120 engagement with the contact 14 and the commutator arm 6 is in engagement with the contact 12, or both of these arms are about to engage with their respective contacts according to the adjustment of the 125 system. To leave the floor, the car operator throws the controller 75 in an appropriate direction which we will assume to be the up direction, the controller being thereby caused to take the position shown 130

in Figure 2 to complete a circuit through the magnet 76 and through the associated switch mechanism to cause the contact 80 to engage with the contact 82. Current immediately flows from the source of power 73 through the wire 72, segment 71, brush 70 and wire 69 to the magnet 53 and from the magnet 53 through the wire 68, brush 67, segment 66 and wire 65 to the magnet 64 whence it passes through the wire 74^a, contact 80, contact 82 and wires 84 and 74 back to the source 73. As a result of this operation, the magnets 64 and 53 are energized, the former tilting up the latch 61 and causing the bridge piece 32 to bridge the contacts 28 and 30 and the latter serving to cause the clutch to tightly grip the sleeve 46. The controller having been moved into operative position, the car starts in an upward direction and by virtue of the operative connection between the sprocket 57 and some moving part of the car operating means, the sleeve 46 is rotated to the left, or counterclockwise. Inasmuch as the clutch is held in gripping relation with the sleeve by the magnet 53 and the clutch unlocked through the elevation of the latch 61, said clutch will be rotated with the sleeve in a counterclockwise direction and the shoe 56 carried by said clutch will be moved to the left until it engages a stop 85 mounted on the plate 45, whereupon the clutch will thereafter slip and will be no longer rotated so long as the shaft 35 continues to rotate and the magnet 53 remains energized.

It will be noted however that during the passage, movement of the clutch from its neutral position into engagement with the stop, it will come into the left-hand dotted line position of Figure 1 and momentarily will serve to bridge the contacts 41^a and 41^b. Such bridging is only momentary and ceases as soon as the shoe, by its continued movement, passes out of engagement with the contact 41^b. However, during this short interval of engagement with both contacts, the restoring magnet 3^a will be energized through the establishment of the following 50 circuit.

From the source of power 16 through wire 24 and branch 27 to contact 28, then through bridge piece 32 to contact 30, and through wires 36 and 37 to the contact 41^b, thence through the shoe 56 to the contact 41^a and through the wire 37 to the switch arm 6 which at this moment is in engagement with the contact 12 and from the contact 12 current flows through the wire 20 to and through the restoring magnet 3^a and passes thence through the wires 18 and 17 back to the source of supply. This momentary energizing of the restoring magnet or its equivalent restoring device effects the 65 restoration of the signals appropriate to

the third floor and for an up direction. It should be borne in mind however that up to the time that the car actually started, in this form of construction, the signals remained operative and that they were not cancelled or restored until the car actually 70 started after stopping.

So long as the car continues in an upward direction, the magnets 53 and 64 will remain energized and the clutch will slip on the sleeve. However, as soon as the controller 75 is thrust in neutral to stop the car, the magnet 76 is de-energized and the switch rocker 77 assumes a neutral position thereby breaking the circuit in which the magnets 64 and 53 are included. Immediately the latch 61 falls to disengage the bridge piece 32 from the contacts 28 and 30 and simultaneously the magnet 53 releases the clutch which being heavier at its lower end gravitates into vertical position and automatically re-engages the latch in the notch 63 to lock the clutch in position until the car is again started, whereupon the operations described are repeated for the particular floor at which the car has stopped. It will be noted that as the clutch moves from engagement with the stop back to its neutral position, the shoe will be caused to wipe over the contacts 41^a and 41^b, but inasmuch as the switch comprising the contacts 28, 30 and 32 is opened no impulse of current through the corresponding circuit will result.

I wish at this point to call attention to the fact that inasmuch as the clutch is driven from some movable part of the car operated mechanism and in synchronism therewith, its movement will have a distinct relation to the movement of the car and since the governor switches 41 and 42 are mounted for pivotal adjustment on the arms 59 and 60, these arms may be adjusted so as to accurately time the restoration of the signals. For example, if the sleeve is geared to the operating mechanism of the car, so as to turn say 10 degrees for every foot of travel of the car, the arm 59 may be positioned at 20 degrees to the vertical so that the governor switch 41 will be closed after the car has moved two feet away from a floor. This example is merely illustrative, but it shows that by adjusting the position of the governor switches, a definite relation can be obtained between the travel of the car and the time of restoration. Those skilled in the art will readily appreciate the importance of this feature from a practical standpoint.

It will of course be understood that while I have described the operations of the system with respect to car II that car I functions in the same manner.

Of course it will be understood that installing a system in accordance with the

showing of Figures 1 and 2, each car is provided with governor apparatus, the magnets 53 and 64 of which are controlled from the controllers of the respective cars, while the governor switches of all of said governors are connected to the up and down restoring magnets which are common to all the cars.

In Figure 3 of the drawing, I have illustrated a wiring diagram showing a modified form of the system for accomplishing the restoration upon the starting of a car after stopping. In this showing 86 is the controller switch of the car and 87 and 88 the up and down motor magnets. 89 and 90 are respectively the up and down governor switches of this particular car and 91 and 92 are the movable arms of up and down commutators for said car. 3^u and 2^u are the up restoring magnets for the third and second floors, respectively, and 3^d and 2^d are the down restoring magnets for the third and second floors. The installation is shown for one car although the wires 93 show the manner in which the connections are made for additional cars. Commutator contacts 94 and 95 are provided for cooperation with the movable arm 91 and contacts 96 and 97 cooperate with the movable arm 92 of the down commutator.

In this showing, the governor switches 89 and 90 are of the character described and claimed in my copending application, Serial No. 496,260, filed August 29, 1921, and are so constituted that when the coils 89^a and 90^a are energized the cores 89^b and 90^b overtravel in an upward direction and actuate the bell cranks 89^c and 90^c to engage the contacts 89^d and 90^d. As the current continues to flow through the coils, the cores return to the magnetic center and permit the bell cranks to gravitate into neutral position to open the circuits previously momentarily established. The operation of this system is as follows.

When the controller is moved from neutral position to start the car and current passed through the appropriate motor magnet, the corresponding coil of the governor switch is energized and actuates the bell crank to cause the depending arm thereof to engage with for example the contact 89^d. If the car is leaving, e. g., the third floor in an upward direction, the commutator arm 91 will be in engagement with the contact 94 so that the following circuit will be momentarily established. From a source of power 98 through wire 99, the bell crank 89^c to the contact 89^d thence through wire 100 to the arm 91 of the commutator and through this arm to contact 94. Thence the current passes through the wire 101 to and through the restoration magnet 3^u and, leaving by the wire 102, passes through the

common return 103 back to the source of supply so that the restoration of the signals appropriate to the up direction of the third floor is accomplished.

In Figure 4, a further modification of the construction employing a single governor switch for each car is disclosed. In this showing 87 and 88 are motor magnets controlled from the car controller 86. 104 is a coil of the governor switch. To one side of this coil is connected a feed line 105 and from the other side of the coil extends a wire 106 having two branches 107 and 108. The wire 107 leads back to the up contact of the controller and has included therein a magnet 109 while the wire 108 leads back to the down contact of the controller and has included therein a magnet 110. These two magnets 109 and 110 are adapted when energized to close normally open switches 111 and 112. The bell crank 113 of the governor switch is connected by wire 114 to a source of current supply 115 and when acted upon by the core 116 of the solenoid is adapted to engage with the contact 117 connected by wiring 118 to the two movable contacts 111 and 112. The cooperating fixed contacts are connected by wires 119 and 120 to the movable arm 121 of the up commutator of the corresponding car and to the movable arm 122 of the down commutator of said car. 3^u is the up restoring magnet for the third floor, 2^u the up restoring magnet for the second floor, 3^d the down restoring magnet for the third floor and 2^d the down restoring magnet for the second floor. The movable arms 121 and 122 move over fixed contacts to selectively place the restoring magnets in circuit in accordance with the position of the car. After the car is at rest at the third floor and is to proceed in an up direction, the controller switch 86 is moved to feed current through the motor magnet 87 and in so doing completes the circuit by way of the wires 107, 106 and 105 through the magnet 109 and the coil 104 in series, so that both of these coils are simultaneously energized. The commutator arm 121 having engaged with fixed contact for the third floor, the circuit is immediately completed by the drawing of the movable contact 111 downwardly by the magnet 109 and by the swinging of the bell crank 113 into engagement with the contact 117 by the core of the solenoid. A momentary impulse of current is thereby passed through the restoring magnet 3^u and restoration is accomplished.

It will be apparent from the foregoing descriptions of the several systems that the invention is susceptible to many embodiments. In fact, it may be carried out in a wide variety of ways, but inasmuch as it is not possible to show all of the ways in which

the invention may be practised, I have advanced these three showings as illustrative without however intending to restrict the invention to such specific embodiments.

5 It will be noted that there is a particular underlying principle common to all of said illustrative showings, namely, that the accomplishment of the restoration depends upon three factors. First, the position of 10 the car in the shaft, second, the act of starting the car or movement thereof as it leaves the floor, and, third, the direction in which said car leaves the floor. In each instance, the travel of a car up and down the shaft 15 effects the automatic selection of the restoration devices to be energized through the use of commutators which close any particular restoration circuit at the desired time and this circuit having been closed by a commutator, the act of starting a car, for example, the shifting of the controller from 20 neutral into a starting position, results either immediately in the closing of a governor switch or causes the car to start so that 25 movement of the car as it leaves the floor will close such governor switch. In the construction of Figure 4, there is only one governor switch, the switches 11 and 12 determining which circuit will be responsive 30 to the operation of the governor switch.

In the construction of Figure 3, as well as in the construction of Figure 1, there are two governor switches for each car, one for the up direction and the other for the down direction. And while in Figure 3 the governor switch is operated immediately upon the throwing of the controller into a starting position, the construction of Figure 1 functions in such manner that the car must 40 actually start before the governor switches can be closed. There are many modifications of which the invention is susceptible, but inasmuch as the method of cancellation of signals herein described is broadly novel, I 45 do not restrict the invention to the specific means employed. That is to say, the present invention is the first, so far as I am aware, capable of accomplishing the restoration of signals with directional selection after a car 50 has stopped at a floor and after the signals have remained set while the car is at rest and irrespective of the direction in which the car may approach or leave said floor. In all prior systems, the car, to cancel the 55 signal as it leaves the floor, must proceed in the same direction in which it approached said floor and this is made unnecessary by the present invention.

It is a vital point, from a practical stand-point, that the floor lamps remain illuminated until the car starts to leave or actually leaves a floor and this with the selective restoration of signals for up and down direction cannot be accomplished by any prior 65 system. It has long been the practice to can-

cel these floor lamps when the car stops at the floor leaving a prospective passenger without means of knowing which car will render the service desired. The present invention entirely obviates this disadvantage 70 and does so in an economical and thoroughly efficient manner.

In the foregoing detailed description and in the accompanying drawings, I have set forth illustrative showings of the present invention, but these showings are to be understood as illustrative, only, and the invention is to be construed as fully commensurate 75 with the appended claims.

Having thus fully described the invention, 80 what I claim as new and desire to secure by Letters Patent is:

1. In an elevator signal restoration system, the combination of a car, up and down restoring magnets for a given floor, a circuit 85 including the up magnet, means for automatically closing said circuit at one point when the car is in proximity with said floor, a second circuit including the down magnet, means for automatically closing said circuit 90 at one point when the car is in proximity with said floor, and means, operable by the starting of the car from said floor in either direction, for selectively completing the co-directional circuit to energize the co-directional magnet. 95

2. In an elevator signal restoration system, the combination of a car, up and down restoring magnets for a given floor, a circuit including the up magnet, a circuit including 100 the down magnet, commutator means for partially completing each of said circuits when the car is in proximity of said floor, and means operable by starting of the car from the floor in either direction for selectively completing the co-directional circuit 105 to energize the codirectional magnet.

3. In an elevator signal restoration system, the combination of a car, up and down restoring magnets for a given floor, each of 110 which magnets forms parts of one of two directional circuits, in each of which is also included a commutator switch, means for operating the commutator switch in accordance with the movement of the car to partially complete said circuit when the car is in proximity to said floor, an additional switch, also included in each of said circuits, and means, operable by starting of the car from the floor in either direction to close 115 said switch when the car leaves said floor in a corresponding direction.

4. In an elevator signal restoration system, the combination of a car, up and down restoring magnets for a given floor, and means, operable by the movement of the car and controlled by the direction of travel thereof, for automatically energizing one or the other of said magnets corresponding 125 130

with the direction of movement of the car upon its departure from said floor and after the car has traversed a predetermined regulable distance in such direction.

5. In an elevator signal restoration system, the combination of a car provided with a controller, up and down restoring magnets for a floor, up and down restoring circuits including said magnets and each of said circuits also including a commutator switch, a preliminary switch, and a circuit completing switch, means for closing the commutator switches when the car is in proximity to said floor, operative connections between the preliminary switch and the car controller to effect immediate closing of one of the preliminary switches when the controller is moved away from neutral position into car operating position and for immediately opening said switch when the car controller is moved into neutral position, and means operable by movement of the car in a direction corresponding to the direction of movement of the car to operate the codirectional completing switch in delayed relation to the operation of the preliminary switch by the controller.

6. In an elevator signal restoration system, the combination of a car provided with a controller, up and down restoring magnets for a floor, up and down restoring circuits including said magnets and each of said circuits also including a commutator switch, a preliminary switch, and a circuit completing switch, means for closing the commutator switches when the car is in proximity to said floor, operative connections between the preliminary switch and the car controller to effect immediate closing of one of the preliminary switches when the controller is moved away from neutral position into car operating position and for immediately opening said switch when the car controller is moved into neutral position, and means operable by movement of the car in the direction selected by said movement of the controller to momentarily operate the codirectional completing switch in delayed relation to the operation of the preliminary switch by the controller.

7. In an elevator signal restoration system, the combination of a car provided with a controller, up and down restoring magnets, up and down restoring circuits including said magnets, commutator means associated with said circuits to partially close said circuits when the car is in proximity to said floor, a preliminary switch, and up and down completing switches included in said circuits, operative connections between the car controller and the preliminary switch to cause immediate closing of the preliminary switch when the car controller is moved out of neutral position into car operating position, and to cause immediate opening of said

switch when the controller is returned to neutral position, a device movable in one direction when the car ascends and in an opposite direction when the car descends to pass the completing switches selectively and to momentarily operate said switches while passing them, said device normally occupying a neutral position between said switches and in engagement with neither when the controller is in neutral position, means to return said device to neutral position when the car is stopped, with sufficient lag to insure opening of the preliminary switch before said device momentarily passes by the completing switch last operated.

8. In an elevator signal restoration system, the combination of a car, a current switching member operatively connected with the operating mechanism of the car to move in one direction when the car travels upwardly and to move in the opposite direction when the car descends, up and down switches on opposite sides of said member in the path of said member to be engaged with and closed thereby as the member is moved in one direction or the other, up and down restoring magnets in circuit with the respective up and down switches, a master switch common to said up and down circuits, means operated by the car controlling mechanism to open said master switch when the car is at rest and to close it when the car is in motion, and commutator means for partially closing the circuits of the up and down magnets when the car is in proximity to the corresponding floor.

9. In an elevator signal restoration system, the combination of a car, a current switching member operatively connected with the operating mechanism of the car to move in one direction when the car travels upwardly and to move in the opposite direction when the car descends, said member normally occupying an intermediate neutral position when the car is at rest, up and down switches on opposite sides of said member and in the path of said member to be momentarily closed thereby as the member is moved in one direction or the other, up and down restoring magnets in circuit with the respective up and down switches, a master switch common to said up and down circuits means operated by the car controlling mechanism to open said master switch when the car is at rest and to close it when the car is in motion, and commutator means for partially closing the circuits of the up and down magnets when the car is in proximity to the corresponding floor.

10. In an elevator signal restoration system, the combination of a car, a current switching member operatively connected with the operating mechanism of the car to move in one direction when the car travels upwardly and to move in the opposite di-

rection when the car descends, said member normally occupying the intermediate neutral position when the car is at rest, up and down switches in the path of said member to be engaged with and closed thereby as the member is moved in one direction or the other, up and down restoring magnets in circuit with the respective up and down switches, a master switch common to said up and down circuits, means operated by the car controlling mechanism to open said master switch when the car is at rest and to close it when the car is in motion, commutator means for partially closing the circuits of the up and down magnets when the car is in proximity to the corresponding floor, and means for locking said member against movement while the car is at rest in a position intermediate the up and down switches.

11. In an elevator signal restoration system, the combination of a car, up and down restoring magnets for a given floor, means for automatically energizing one or the other of said magnets correspondingly with the direction of movement of the departure of the car from said floor and after the car has traversed a predetermined distance in such direction, said means including spaced apart stationary switch elements, and a movable switch element normally free from engagement with either of said stationary switch elements, but movable in co-directional synchronism with the car into engagement with one of them to effect the automatic energizing of the appropriate magnet.

12. In an elevator signal restoration system, the combination of a car, up and down restoring magnets for a given floor, means for automatically energizing one or the other of said magnets correspondingly with the direction of movement of the departure of the car from said floor and after the car has traversed a predetermined distance in such direction, said means including spaced apart stationary switch elements, and a movable switch element normally free from engagement with either of said stationary switch elements, but movable in co-directional synchronism with the car into engagement with one of them to effect the automatic energizing of the appropriate magnet, said spaced apart stationary switch elements being manually movable toward and away from one another to regulate the time required for the movable switch element to move from a normally neutral position between them into engagement with either of them.

13. In an elevator signal restoration system, the combination of a car, up and down restoration devices for each of several floors, electric circuits associated with said devices, commutator means moving in synchronism

with the car for automatically partially completing the circuits of both the up and down restoration devices when the car is in proximity to the corresponding floor, and means governed by the stopping and subsequent starting of the car for finishing the completion of the circuit appropriate to the co-directional restoration device at such floor.

14. In an elevator signal restoration system, the combination of a car having a car controller, up and down restoring magnets for a given floor, a circuit for each magnet and each of which circuits includes a plurality of switches, all of which must be closed to complete the corresponding circuit to energize the corresponding magnet, means controlled by the car controller when in car operating position to close one switch in the co-directional circuit, means movable in timed relation with the car to close another switch in the co-directional circuit, and means controlled by the starting of the car to close a third switch in such co-directional circuit.

15. In an elevator signal restoration system, the combination of a car having a car controller, up and down restoring magnets, each of which is included in a co-directional electric circuit which also includes a commutator switch, a preliminary switch, and a completing switch, means for moving each commutator switch in accordance with the movements of the car, means operatively connected to the controller of the car to close one of the preliminary switches when the controller is moved from neutral position into car operating position, and means automatically operable upon movement of the car in the direction selected by the controller to close the co-directional completing circuit whereby the co-directional electric switch is fully completed.

In testimony whereof I have signed the foregoing specification.

FRANZ A. BOEDTCHER.
